DEEP WELL PUMP

William B. Erb, Chicago, Ill.

Application April 2, 1936, Serial No. 72,303

3 Claims. (Cl. 103—192)

This invention relates to double-acting pumps for deep wells, and its purpose is to provide an improved pump of this type adapted for economical production and involving some simplification as compared with previous pumps of this character. It consists of certain features and elements of construction in combination as herein shown and described and as indicated by the claims.

10 In the drawing:

Figure 1 is an axial section of a pump embodying this invention.

Figure 2 is an axial section of the upper portion of the pump casing and its head fitting showing the valve in open position, and being taken at right angles to the plane of Figure 1 to show certain details of the piston structure.

Figure 3 is a transverse section taken as indicated at line 3—3 on Figure 1.

Figure 4 is a transverse section taken as indicated at line 4—4 on Figure 1.

Figure 5 is a transverse section taken as indicated at line 5—5 on Figure 1.

Figure 6 is a transverse section taken as indicated at line 6—6 on Figure 1.

As shown in the drawing, the pump cylinder comprises a shell 1 threaded at its lower end for connection with a fitting 2 and threaded at its upper end for connection with a head fitting 3. At the lower end a valve seat member 4 is snugly fitted into the fitting 2 with its flange 4^a resting on a shoulder 2^a thereof. A ball valve 5 is retained adjacent the valve seat by a cage 6 which is screwed onto the externally threaded seat portion of the member 4, incidentally serving to retain thereon an encompassing cup leather 7.

The cylinder head fitting 3 includes an upwardly opening, internally threaded portion 3^a adapted to connect with the well casing, not shown, and below this portion there is inserted a head member 8 tapered at 8^a to seat in the tapered portion of the bore of the fitting 3. The head 8 includes an axially located and rather elongated guide bearing 9 for the pump rod 10, and at the upper end this guide terminates in a threaded portion onto which there is screwed an annular metallic member 11 forming a stuffing box with packing 12 enclosed and clamped against the end of the guide. Externally, the member 11 fits into a cup leather 13 which is lodged upon the transverse end wall 8^b of the head 8 and bears against the bore of the head fitting 3 to supplement the taper 8^a in sealing the head into the fitting 3. The upper edge of

the cup leather 13 is thus exposed to the pressure of the water column in the well casing, rendering it self-sealing to a certain extent.

Just below the transverse wall 8^b the head fitting 3 and the head 8 are provided with registering ports 14 and 15 to communicate with downwardly open ports 16 in the head 8, controlled by an annular valve member 17, which may be of rubber or other suitably compressible material. The valve 17 is held to its seat by a flanged ring 18 slidably movable over the external surface of the guide 9 and yieldingly urged toward the valve seat by a coil spring 19 reacting against a flanged collar 20 which is screwed onto the lower end of the guide 9.

It will be understood that the ball valve 5 acts as a check valve controlling inflow of water into the lower end of the pump casing during the upstroke of the piston while the ports 14, 15 and 16 and the valve 17 permit the intake of water into the upper end of the pump casing during the down-stroke of the piston.

The piston comprises a central hollow casting 21 whose bore terminates upwardly in a valve seat 22 controlled by a ball valve 23 and affording communication with the chamber of a shell 24 which forms the upper end of the piston and is connected thereto by threads at 25. A hollow bridge 26, extending across the chamber of the shell 24, opens downwardly through a port terminating in a valve seat 27 positioned directly over the ball valve 23, so that on the down-stroke of the piston the valve is lifted from its seat 22 and shifted to the seat 27. The bridge 26 opens laterally through the shell 24 at ports 28, and adjacent these ports the external wall of the shell 24 is cut down to afford a clearance space 29 for the flow of water passing through the ports 28.

The piston is packed in substantially the usual manner, by means of cup leathers 30 carried on its cylindrical body portion 21 and retained in position by a terminal fitting 31 screwed onto the lower end of said body. Preferably, this fitting 31 is formed as a yoke supporting an internally threaded annular part 32, and the valve cage 6 is also provided with a centrally threaded annulus 6^b at its upper end, so that if it is desired to remove the valve 6, with its valve 5, the piston may be lowered with a threaded nipple 50 (not shown) screwed into the part 32 and then by rotating the piston the nipple may be engaged with the threads of the part 6^b, serving as a temporary coupling for hoisting the valve cage.

The operation of the pump and its valves, as just described, is as follows: Upon the up-stroke of the piston its ball valve 23 is seated at 22, and the suction in the lower part of the casing 1 draws water into the lower fitting 2 past the ball valve 5. At the same time, any water in the casing above the piston is forced into ports 28 of the bridge 26, and thence through port 27 into the chamber of the shell 24, and upwardly 10 through the hollow pump rod 10.

At its upper end the first section 10 of the pump rod is connected to the next section 10^a by a guide and coupling member 40, which includes a central threaded sleeve portion 41 into 15 which the pump rod sections 10 and 10^a are entered from opposite ends. The sections 10 and 10^a are spaced apart in the coupling, and the coupling sleeve 41 is formed with ports 42 through which the water may escape from the 20 interior of the pump rod. Radial web portions 43, connect the central portion 41 with an outer cylindrical wall 44, which fits loosely in the well casing (not shown) for guiding the pump rod as it reciprocates therein.

Upon the down-stroke of the piston the check valve 5 is seated, thus trapping in the lower portion of the pump cylinder the water which has entered during the up-stroke, and, as the piston descends, this water passes up through 30 the hollow body 21, past the check valve 23, into the chamber of the shell 24, and up through the pump rod 10 for escape at the ports 42. The downward movement of the piston producing suction in the upper portion of the cylinder 1 opens the annular valve 17, in opposition to the 35 force of its spring 19, drawing water through the ports 14 and 16 into the upper end of the cylinder 1.

It will be noted that in the design of the cylinder head fittings all the parts of the head 8 below the tapered seat 8^a are within the small diameter of said tapered seat, so that for the purpose of repair or replacement the cylinder head may be 40 readily removed by merely pulling up on the pump rods with sufficient force to dislodge the head from its tapered seat. The valve 17, with its spring and retaining collar 20, will then pass upward through the cylinder head fitting 3 and 45 through the well casing.

I claim:

1. In a double-acting pump including a pump cylinder, a cylinder head fitting comprising a cylindrical member connected at its lower end 50 to the pump cylinder and adapted for connection at its upper end to a well casing, said member having a straight cylindrical bore adjacent its upper end continuing in a downwardly tapering bore, with a lateral inlet port disposed between 55 said straight and tapering bores, a removable cylinder head having a tapered portion to seat in the tapered bore and having a lateral inlet port leading to the cylinder and registering with that of the head fitting when the head is so seated, together with an upwardly open cup 60 leather secured to the top of the head with its cylindrical portion engaging the wall of the straight cylindrical bore of the head fitting and

with the edge of said portion exposed upwardly to the pressure in the well casing.

2. In a double-acting pump including a pump cylinder, a cylinder head fitting comprising a cylindrical member connected at its lower end 5 to the pump cylinder and adapted for connection at its upper end to a well casing, said member having a straight cylindrical bore adjacent its upper end, a removable cylinder head having a transverse end wall dimensioned to fit in 10 said cylindrical bore of the fitting with a central upstanding annular portion externally threaded and internally bored to serve as a pump rod guide, an upwardly open cup leather seated upon said end wall of the cylinder head with its cylindrical portion engaging the cylindrical wall of the head fitting and a downwardly open cup-shaped cap member screwed onto the threaded annular guide within the cup-leather for securing the cup leather in position, together with 15 packing confined within the cup form of said cap and clamped thereby against the end of said threaded annular guide, thus forming a stuffing box for a pump rod.

3. A double-acting pump comprising a cylinder, a fitting at the lower end thereof comprising an inlet port and a downwardly seating check valve thereon, a cylinder head fitting comprising a cylindrical member connected at its lower end to the pump cylinder and adapted for connection at its upper end to a well casing, said member having a straight cylindrical bore adjacent its upper end continuing in a downwardly tapering bore, with a lateral inlet port disposed between said straight and tapering 30 bores, a removable cylinder head having a tapered portion to seat in the tapered bore and having a lateral inlet port leading downwardly into the cylinder and registering with that of the head fitting when the head is so seated, an upwardly seating check valve in the upper end 35 of the cylinder controlling said port, said cylinder head having a transverse end wall dimensioned to fit in the cylindrical bore of the head fitting with a central upstanding annular portion externally threaded and internally bored to serve as a pump rod guide, an upwardly open cup leather seated upon said end wall of the cylinder head with its cylindrical portion engaging the cylindrical wall of the head fitting, a downwardly open cup-shaped cap member screwed onto the threaded annular guide within the cup leather for securing the latter in position, packing material confined within the cup form of said cap and clamped thereby against the end of said threaded annular guide to form a stuffing box 40 for a pump rod; a piston in the cylinder with a hollow piston rod passing through said guide and provided with a port discharging above the cylinder head, said piston including a downwardly open passage with a downwardly seating ball valve controlling it, a port spaced above said valve adapted to be closed thereby, a passage leading from said port through the piston into the upper portion of the cylinder, and a by-pass 45 through the piston around said port leading to the hollow piston rod.
